DIPPER DOOR LATCH RELEASE

Filed July 17, 1929

32 INVENTOR:—
Tagar R. Culver.
By Martin P. Smith, ^{App'd.} A. S. J.

UNITED STATES PATENT OFFICE

LAGAR R. CULVER, OF LOS ANGELES, CALIFORNIA, ASSIGNOR TO FREDERICK FALKNER,
OF LOS ANGELES, CALIFORNIA

DIPPER DOOR LATCH RELEASE

Application filed July 17, 1929. Serial No. 378,905.

My invention relates to a dipper door latch release and has for its principal object, the provision of a relatively simple and practical fluid pressure actuated device that may be conveniently employed, for releasing the latch that is associated with the dipper door of a steam or gas-air shovel.

Heretofore, it has generally been the practice to release dipper door latches by the manual operation of a cable, chain or like flexible member and it is one of the objects of my invention to provide a fluid pressure actuated lever, the operation of which is controlled by a foot pedal, and which lever when moved under the influence of fluid pressure, will exert pull upon the flexible member that leads to the dipper door latch, thereby actuating the latter to effect the release of the dipper door.

Further objects of my invention are to provide a dipper door latch releasing apparatus that is capable of being conveniently located on the boom or arm of the steam or gas-air shovel, to provide simple and efficient means for cushioning the lever of the device at both ends of its stroke, and further to provide a device of the character referred to that is strong and durable in construction, positive in operation and very effective in performing the functions for which it is intended.

With the foregoing and other objects in view, my invention consists in certain novel features of construction and arrangement of parts that will hereinafter be more fully described and claimed and illustrated in the accompanying drawings, in which—

Fig. 1 is a side elevational view of a portion of a steam or gas-air shovel with its boom and showing my improved dipper door latch release in position for use thereupon.

Fig. 2 is a plan view looking in the direction indicated by the arrow 2 in Fig. 1 and showing the pedal that is utilized for actuating the releasing device.

Fig. 3 is an enlarged horizontal section taken on the line 3—3 of Fig. 1.

Fig. 4 is an enlarged horizontal section taken on the line 4—4 of Fig. 1.

Fig. 5 is an enlarged vertical section taken on the line 5—5 of Fig. 1.

Referring by numerals to the accompanying drawings which illustrate a practical embodiment of my invention, 10 designates the body or platform of a steam or gas-air shovel, 11 the boom or swinging arm, 12 the dipper sticks, 13 the drum upon which winds the cable 14 that leads to the dipper door latch, 15 the swinging bracket that carries pulley 16 over which the cable 14 passes and which swinging bracket and pulley are adapted to take up the bight of cable 14 when the latch is released.

All of the parts just described are of well known construction and are utilized in standard forms of steam and gas-air shovels now in general use.

My improved dipper door latch release includes an upright bracket 17, preferably cast metal, said bracket having a base plate 18 that is firmly secured to the boom or arm 11 by means of bolts 19, and said base plate being arranged so that the body of the upright bracket 17 occupies a vertical position slightly beyond one side of the boom or arm.

Formed on the upper portions of the front and rear upright members of bracket 17, are bearings 20 for a piston rod 21, and which latter projects forwardly into a small cylinder 22 that is secured in any suitable manner to the front upright member of bracket 17. Mounted on the forward end of this piston rod and arranged for operation within the cylinder 22, is a piston 23.

A fluid pressure supply pipe 24 leads from a suitable source of supply to the forward end of cylinder 22, and located in said pipe, preferably at a point immediately adjacent to the cylinder 22, is an ordinary 3-way valve 25, and the outer stem of which valve carries a short arm or lever 26.

Mounted in suitable bearings 27 on the platform 10, preferably at a point immediately in front of the station occupied by the operator of the shovel, is a rockshaft 28 that is actuated by pressure that is applied to a conveniently located pedal 29. Carried by rockshaft 28 is a short arm 30 and connecting said arm with the arm 26 of the 3-way valve,

is a flexible member 31 preferably a wire or small cable.

Pedal 29, rockshaft 28 and arms 26 and 30 are arranged so that when the pedal is depressed, the 3-way valve will be shifted into position whereby fluid pressure may pass thru pipe 24 into the cylinder 22 in front of the piston 23 therein, and when the 3-way valve returns to its normal position, the steam or fluid pressure that entered the cylinder is free to exhaust thru a port in the valve housing.

Seated in the lower portion of bracket 17 is a transversely disposed shaft 30^a and journaled on the ends thereof are the lower ends of a pair of upright arms 31^a that extend alongside and above the arcuate top member 32 of the frame 17, and secured to the upper ends of these arms is an upwardly projecting arm 33. A flexible member 34, preferably a cable, connects the upper end of arm 33 with the housing of pulley 16 that is carried by the lower end of the swinging arm 15.

Fixed on that portion of the piston rod 21 that is positioned between the bearings 20, is a block 35 and projecting outwardly from the sides thereof, thru slots 36 that are formed in the arms 31, are trunnions 37.

Formed integral with the arms 31 just above the arcuate top member 32 of the bracket are housings 38, the ends of which are spaced apart to provide openings 39 and arranged between these housings is a relatively stiff coil spring 40.

Formed integral with and projecting upwardly from the ends of the arcuate top member 32, are blocks 41 against which the ends of the spring 40 are adapted to engage when the arms 31 are swung from one position to another. Detachably connected in any suitable manner to the rear one of the blocks 41, is the upper end of a brace 42, the lower end thereof being fastened to the top of the boom or arm 11, preferably on the side opposite from the side on which the bracket 17 is mounted.

Connected to the lower portions of the arms 31^a and to a bracket that depends from the cylinder 22, is a retractile coil spring 43 that normally holds the arms at the forward end of their travel, as illustrated in Fig. 1, and for the accommodation of this spring, an opening 44 is formed thru the forward portion of the base plate 18.

Under normal conditions, or while the 3-way valve is open, the parts of my improved door latch release occupy the positions as illustrated in Fig. 1, and when so positioned, the latch to which the cable 14 is connected is positioned so as to retain the dipper door in closed position.

To operate the latch release, pedal 29 is depressed, thereby rocking shaft 28 so as to pull rearwardly upon wire 31, thus shifting the 3-way valve into position to permit fluid pres-

sure to pass from pipe 24 into the outer end of cylinder 22, and this fluid pressure moves piston 23 rearwardly within the cylinder. The trunnions 37 on block 35 that are carried by the piston rod, engage the arms 31^a and swing the same rearwardly against the resistance offered by retractile spring 43, and thus the arm 33 is swung rearwardly or away from the outer end of the boom with the result that arm or bracket 15 will be swung upon its pivot, thereby exerting pull on the cable 14 and withdrawing the dipper door latch from its keeper so as to permit the door to open.

The 3-way valve 25 is provided with a spring that acts to return the valve to its normal open position when pressure on the pedal 29 is released, and when such action takes place, the fluid pressure previously admitted to the cylinder 22 in front of piston 23 is permitted to exhaust thru the 3-way valve and under the influence of retractile spring 43, the arms 31^a and arm 33 will be returned to their normal forward positions, and thus the parts of the releasing device will be set or positioned for a subsequent releasing operation.

As the arms 31^a swing from one position to another, the ends of the spring 40 will contact with the blocks 41, thereby serving to cushion the arms at the ends of their travel, and which cushioning effect eliminates pounding and undue vibration.

Thus, it will be seen that I have provided a dipper door latch that is relatively simple in construction, capable of being installed and used on practically all forms of steam or gas-air shovels and which release provides efficient and convenient means for effecting and withdrawal of the latching bolt that normally retains the dipper door in closed position.

It will be understood that minor changes in the size, form and construction of the various parts of my improved dipper door latch may be made and substituted for those herein shown and described without departing from the spirit of my invention, the scope of which is set forth in the appended claims.

I claim as my invention:

1. In a dipper door latch release, a frame adapted to be positioned on the boom of a steam or gas-air shovel, an arm mounted for swinging movement on said frame, an arcuate member at the top of said frame, which arcuate member is concentric with the axis of the swinging arm, a connection from said arm to the latch of the dipper door that is carried by said boom, fluid pressure actuated means for moving said arm in one direction, a spring connected to said arm for moving same in the opposite direction, and cooperating means carried by said arm and arranged on the ends of the arcuate top member of the frame for cushioning said swinging arm at both ends of its swinging movement.

2. In a dipper door latch release, a frame adapted to be positioned on the boom of a

steam or gas-air shovel, an arm mounted for swinging movement on said frame, an arcuate member at the top of said frame, which arcuate member is concentric with the axis of the swinging arm, a connection from said arm to the latch of the dipper door that is carried by said boom, fluid pressure actuated means for moving said arm in one direction, a spring connected to said arm for moving same in the opposite direction, cooperating means carried by said arm and arranged on the ends of the arcuate top member of the frame for cushioning said swinging arm at both ends of its swinging movement, and pedal actuated means for controlling said fluid pressure actuated means.

3. The combination with the shovel carrying boom of a steam or gas-air shovel, of a frame mounted on said boom, an arm mounted for swinging movement on said frame, a connection from said arm to the door latch of the dipper that is carried by said boom, pedal controlled fluid pressure actuated means for imparting swinging movement to said arm, a housing on the intermediate portion of said swinging arm, a spring loosely arranged within said housing, and stops on the upper portion of said frame for engaging said spring at both ends of the swinging movement of said arm.

4. In a dipper door latch release, a frame adapted to be positioned on the boom of a steam or gas-air shovel, an arm mounted for swinging movement on said frame, a housing formed on the intermediate portion of said arm above said frame, a spring within said housing, stops on the upper portion of said frame for engaging the ends of said spring at the ends of the swinging movement of said arm, a cylinder mounted on said frame, a piston arranged for operation within said cylinder, which piston is connected to the swinging arm and means for admitting fluid pressure to said cylinder in front of the piston therein.

5. In a dipper door latch release, a frame adapted to be positioned on the boom of a steam or gas-air shovel, an arm mounted for swinging movement on said frame, a housing formed on the intermediate portion of said arm above said frame, a spring within said housing, stops on the upper portion of said frame for engaging the ends of said spring at the ends of the swinging movement of said arm, a cylinder mounted on said frame, a piston arranged for operation within said cylinder, which piston is connected to the swinging arm, means for admitting fluid pressure to said cylinder in front of the piston therein, and a spring for restoring said arm to its normal position after movement by the fluid pressure actuated piston.

6. In a dipper door latch release, a frame adapted to be positioned on the boom of a steam or gas-air shovel, said frame having

side members, an arm mounted for swinging movement on said frame, a cylinder mounted on said frame, a piston arranged for operation within said cylinder, a piston rod secured to said piston and mounted for sliding movement through bearings in the side members of said frame, a block mounted on said piston rod between the side members of said frame, a sliding pivotal connection between said block and swinging arm, means for admitting fluid pressure to said cylinder in front of the piston therein, a spring for restoring said arm to its normal position after movement by the fluid pressure actuated piston, and means for cushioning said arm at both ends of its swinging movement.

In testimony whereof I affix my signature.
